UNITED STATES PATENT OFFICE.

VINTON E. SISSON, OF CHICAGO, ILLINOIS, ASSIGNOR TO WALTER P. MURPHY, OF CHICAGO, ILLINOIS.

METAL END STRUCTURE FOR RAILWAY-CARS.

1,244,908.

Specification of Letters Patent.

Patented Oct. 30, 1917.

Continuation in part of application Serial No. 665,098, filed December 11, 1911. This application filed March 13, 1916. Serial No. 83,826.

To all whom it may concern:

Be it known that I, VINTON E. SISSON, a citizen of the United States, residing at Chicago, in the county of Cook and State of Illinois, have invented certain new and useful Improvements in Metal End Structures for Railway-Cars, of which the following is specification.

My invention relates to the construction of freight cars, particularly box cars, and has for its object to provide a new and improved all-metal end structure for box cars which may either form a part of the car when first built or may be readily and conveniently placed upon an old car when the wooden end has become broken or injured.

The ends of box cars are peculiarly liable to become broken and injured due to the fact that the cargo has a tendency to shift back and forth when the train starts and stops. If the car is loaded with heavy articles, such as rails, piping, lumber, or the like, the shifting of such articles is likely to break out the end of the car or wrench the end sheathing away from the sills and posts. My present invention provides a very strong and durable end structure consisting of a plurality of sheets of metal joined together by vertically extending bands preferably formed of pressed steel. Preferably both the end sheets and the connecting bands are formed with ribs or corrugations. In order to give the structure strength and rigidity the ribs or corrugations on the end sheets preferably run horizontally so that they stand at right angles to the reinforcing rib or ribs provided by the connecting bands.

This application is a continuation, so far as the construction shown in Figures 1 to 3, inclusive, is concerned, of applicant's pending application Serial No. 665,098, filed December 11, 1911.

The invention is illustrated, in certain preferred constructions, in the accompanying drawings, wherein—

Fig. 1 is an end elevation of the railway box car provided with the sheet metal end of my invention;

Fig. 2, a sectional view taken on line 2—2 of Fig. 1, looking in the direction of the arrows;

Fig. 3, a sectional plan taken on line 3—3 of Fig. 1;

Fig. 4, an end elevation illustrating a modified construction, and

Fig. 5, a sectional plan taken on line 5—5 of Fig. 4, with a portion of the flooring broken away.

Like characters of reference indicate like parts in the several figures of the drawings.

Referring first to Figs. 1 to 3 inclusive, 10 designates the corner posts of a box car of ordinary construction, 11 the ridge pole, 12 the flooring and 13 the draft sills. The end 65 structure consists of two end sheets 14, 14 extending from the top to the bottom of the car and connected at the center by a connecting band or post 15. The end sheets are formed with the horizontal corrugations or 70 ribs 16 and with flanges 17 on their outer vertical edges which are secured to the corner posts 10 by the bolts 18. In the construction shown, although this is not essential, the usual end plate is done away with 75 and the purlins 19 rest upon inturned flanges 20 formed at the upper edges of the end sheets 14. The ridge pole 11 rests upon a similarly formed flange 21 on the connecting band 15 and a clip 22 is employed for 80 holding the ridge pole in position, which clip is secured to the flange 21 by rivets 23 and to the ridge pole by bolts 24. The connecting band 15 is formed with a hollow rib 25 which is widest and deepest at the center 85 and tapers down toward its extremities. The edges of the end sheets overlap the flat portions or flanges of the band 15 coming close up to the rib 25 so that watertight joints are provided. The connecting band 90 15 not only serves to connect together the end sheets and to reinforce, strengthen and rigidify the end structure but is well calculated, when formed as shown and described, to serve as a post to take some of 95 the roof load.

The lower edges of the end sheets may be secured to the body of the car in any desired manner. I have shown the sheets provided with inturned flanges 26 riveted to the in-turned flange 27 of the connecting band 15 and secured to the draft sills 13 by means of the gusset plates 28 and casting 29, the casting 29 being riveted to the sides of the draft sills and the gusset plates 28 riveted to the 105 castings through the flanges 26. If desired, the flanges 17 on the outside edges of the end sheets may be secured to the side sills 30 by

means of the gusset plates 31. With this construction, by means of which the end sheets are attached to the side sills and draft sills of the car, the ordinary end sill may be dispensed with and in place of it the comparatively light nailing strip 32 employed for supporting the flooring 12.

In Figs. 4 and 5 a modified construction is shown. The end, in this case, consists of 10 three horizontally corrugated ribbed end sheets 33, 34, 35, and of two connecting bands or posts 36. The bands, in this case, are shown as overlapping the margins of the end sheets providing a construction better 15 capable of resisting thrust from the inside of the car although the joints provided are perhaps not so thoroughly water tight. The end sheets are shown as provided on their lower edges with inturned flanges 37 20 secured to the inturned flanges 38 of the connecting bands and to the draft sills 13 of the car by means of the devices employed in the other construction. The construction shown in Figs. 4 and 5 may be in other respects like 25 that illustrated in the first three figures.

I claim:

1. The combination with a box car, comprising a ridge pole and an underframe, of a sheet metal end structure for the same 30 comprising end sheets extending from top to bottom of the car and formed with horizontal corrugations, and a connecting member to which the adjacent vertical edges of the end sheets are secured which extends 35 from the ridge pole of the car to the underframe, is connected with said ridge pole and underframe, and is formed with an outwardly projecting reinforcing rib.

2. An end structure for railway box cars, 40 comprising two metal end sheets and a pressed steel connecting and roof-supporting member extending centrally of the end structure from the top of the car to the bottom and formed with a hollow reinforcing rib 45 and with flanges to which the vertical edges of the end sheets are secured, said rib being widest and deepest at the center and tapered down toward each end.

3. An end structure for freight cars, comprising 50 two metal end sheets formed with horizontal corrugations and a pressed steel connecting and reinforcing member extending centrally of the end structure from the top of the car to the bottom, and formed 55 with a hollow reinforcing rib and with flanges to which the vertical edges of the end sheets are secured, said rib being widest and deepest at the center and tapered down toward each end.

60 4. A car end composed of sheet metal, the central portion of which is offset with respect to the side portions and said side portions each being provided with a vertically disposed row of horizontally arranged corrugations.

5. A car end comprising three vertically disposed panels, the outer ones of which are provided with horizontally disposed corrugations, and the central one of which sections or panels occupies a position in front 70 of the plane occupied by said side panels.

6. A car end constructed of sheet metal having a vertically extending, centrally arranged offset reinforcing and stiffening portion, and the remaining portions of the sheet 75 metal being provided with horizontally disposed ribs or corrugations.

7. A car end constructed of sheet metal having a vertically extending, centrally arranged offset reinforcing and stiffening portion, and the portions to the sides of said 80 centrally arranged portion being provided with stiffening ribs or corrugations.

8. The combination with the underframe and ridge pole of a box car, of an end structure for the car comprising a pair of sheet metal panels extending from top to bottom of the car, and a centrally arranged stiffening and connecting member to which said panels are secured, which is provided with 90 flanges secured to said ridge pole and underframe.

9. The combination with the underframe and roof structure of a box car, of an end structure for the car comprising a pair of 95 sheet metal panels having flanges secured to said underframe and to said roof structure, and a centrally arranged connecting and reinforcing member to which said panels are secured, and which is provided with flanges 100 secured to said roof structure and underframe.

10. The combination with the underframe and roof structure of a box car, of an end structure for the car comprising a pair of 105 sheet metal panels having flanges secured to said underframe and to said roof structure, and a centrally arranged connecting and reinforcing member to which said 110 panels are secured, and which is provided with flanges secured to said roof structure and underframe, said reinforcing member being provided with a vertical corrugation and said panels with horizontal corrugations.

11. An end structure for railway box cars, comprising two metal end sheets and a pressed steel connecting and roof-supporting member extending from the top of the car to the bottom and formed with a hollow 120 reinforcing rib, and with flanges to which the vertical edges of the end sheets are secured.

12. An end structure for railway box cars, comprising two metal end sheets and a 125 pressed steel connecting and roof-supporting member extending from the top of the car to the bottom and formed with a hollow reinforcing rib, and with flanges to which the vertical edges of the end sheets are secured,

said rib being widest and deepest at the center and tapered toward each end.

13. An end structure for freight cars, comprising two metal end sheets formed with 5 horizontal corrugations, and a pressed steel connecting and reinforcing member extending from the top of the car to the bottom and formed with a hollow reinforcing rib and with flanges to which the vertical edges 10 of the end sheets are secured, said rib being widest and deepest at the center and tapered toward each end.

14. An end structure for a box car, comprising a pair of sheet metal panels, each of 15 which is secured at the bottom to the end of the underframe and is provided at the top with an inturned flange for supporting the roof of the car, and a centrally arranged roof-supporting and reinforcing element for 20 said structure, comprising a hollow sheet metal member rigidly united with said panels and extending vertically of the structure substantially from top to bottom thereof.

15. An end structure for a box car, comprising a pair of sheet metal panels, each 25

of which is secured at the bottom to the end of the underframe and is provided at the top with an inturned flange for supporting the roof of the car; and a reinforcing element for said structure, comprising a sheet 30 metal member rigidly united with said panels having an inwardly exposed concavity which is widest and deepest at its center and tapers toward the ends of the member, said member extending vertically of the structure 35 substantially from top to bottom thereof.

16. An end structure for a box car, comprising a pair of sheet metal panels, each of which is secured at the bottom to the end of the underframe and is provided at the 40 top with an inturned flange for supporting the roof of the car; and a centrally arranged roof-supporting and reinforcing element for said structure, comprising a sheet metal member rigidly united to said panels having an inwardly exposed concavity, said member extending vertically of the structure 45 substantially from top to bottom thereof.

VINTON E. SISSON.
